FIREARM

Michael J. Sobran, Woodbridge, Conn., assignor to Olin Mathieson Chemical Corporation, a corporation of Virginia

Filed Aug. 3, 1964, Ser. No. 81,126

Term of patent 14 years

(Cl. D30—1)

FIG. 1

FIG. 2

FIGURE 1 is a side elevational view of a firearm embodying my new design.

FIGURE 2 is a fragmentary enlarged view in side elevation of the fore-end portion of the firearm shown in FIGURE 1.

The essential feature of my design resides in the portion shown in full lines in the drawings.

The undisclosed side of the firearm is substantially the same in appearance as the shown side.

I claim:

The ornamental design for a firearm, as shown and described.
